UNITED STATES PATENT OFFICE

EDWARD B. HESS, OF NEW YORK, N. Y., ASSIGNOR TO ROYAL TYPEWRITER COMPANY,
OF NEW YORK, N. Y., A CORPORATION OF NEW JERSEY.

TYPE-WRITING MACHINE.

950,326.

Specification of Letters Patent. Patented Feb. 22, 1910.

Application filed September 25, 1909. Serial No. 519,614.

To all whom it may concern:

Be it known that I, EDWARD B. HESS, a citizen of the United States of America, residing in the borough of Manhattan, city, county, and State of New York, have invented a certain Improvement in Type-Writing Machines, of which the following is a specification.

This invention relates to means for controlling cards and sheets being printed upon. It is shown applied to a front-strike machine with a vertically shifttable carriage known as the "Royal Standard."

In the accompanying drawings:—Figure 1 is a top plan view; Fig. 2, a front elevation; and Fig. 3, a transverse section just inside the right hand end plate of the carriage.

The several features of novelty in the illustrated organization may be capable of use independently. Their combined use, however, affords efficient results in respect to the control in the machine of cards and sheets being printed upon.

One of the features of this invention is a card guide and holder arranged closely adjacent the printing surface of the platen. It has two arms or bifurcations 1, 1, extending vertically in front of the platen on each side of the point at which printing occurs and carries a scale 2 adjustably mounted thereon. The arms are carried by a plate 3 of suitable contour attached to the shift rail 4 of the carriage so that the relation between the scale and platen will be maintained either in normal or shifted position of the carriage. The upper ends of these arms are adapted, formed or equipped to hold a card or sheet against the printing surface of the platen and direct it rearwardly therefrom. The edge of the scale 2 is designed to be at and parallel with the line of print. To provide means for its accurate adjustment in assembling the machine to compensate for minute variation of proportions or relationship in manufacture, it is adjustably mounted upon its supporting arms 1 in any appropriate way. The means shown in the present instance comprise slots 5 in the arms 1, indicated in dotted lines in Fig. 2, coöoperating with adjusting clamping screws working in tapped apertures in the scale plate and extending through the vertical arms. When the plate 3 is attached to the shift rail 4 as it may be

by means of screws 7, the scale plate or bar 2 may then be adjusted with accuracy to the printing line on the platen. Such a two piece card holder or guide having capacity for adjustment as to position is, so far as I am aware, new in this art.

Another feature of the invention relates to the means located at or forming a part of the upper ends of the arms 1 and acting to hold and rearwardly deflect a card or sheet 65 being printed on. This part of the invention comprises rolls mounted to turn freely on vertical pins or roller shafts carried at the upper ends of the parts 1. As shown, these parts 1 are turned over at the ends to 70 form flat projections 8 extending toward the front of the machine and in such parts 8 are fixed the roller shafts or spindles 9 upon which the rollers 10 are mounted to turn freely. Each of these rollers is of irregular 75 diameter, that is to say, their diameter increases from the bottom upwardly so that the side of the roller in elevation shows as a curved line. This curved line may be and preferably is such as to follow the curve of 80 the platen closely adjacent the surface thereof. The effect is to facilitate the passage of a card as the carriage feeds and to guide it rearwardly in its discharge from the platen. This arrangement and construction of the 85 card guide or holding roller is, so far as I am aware, a novelty in this art.

The scale plate beyond or outside of the vertical arms 1 is at its ends preferably deflected toward the front of the machine and 90 equipped with rounded knobs, this latter feature being merely for protection of the hands of the operator.

I prefer to employ in coöperation with the card holder and guide, guiding rolls 12, 12, 95 located (when in operation) on opposite sides, respectively, of the printing point and adjacent the ends of the holding and guiding arms 1. These rolls are on the transverse rod 13 of a bail whose arms 14 are hinged 100 on a transverse carriage rod 15 in rear of the platen. This latter rod may be and is, as shown, the tabulator rod of the machine. On the upper edge of each arm 14 are two separated outwardly turned lugs 105 16, 16, between which is a coiled spring 17 through which and the lugs passes a headed rod 18 the rounded rear end of which works against the edge of a bracket 19 attached to bar 15. The organization is such that when 110

the bail is thrown upward out of operation it is held up and when drawn down it is held down and spring pressed.

The space between the arms 1, 1, and rolls 5 10, 10 is sufficient for the reception of the ordinary ribbon vibrator (not shown) which may be so placed that when in normal, or low, position it will not cover the edge of the scale 2. This scale extends between the arms 10 and preferably beyond them and serves both as a platen scale and carriage scale. It has a notch in its upper edge between the arms which is an impression point indicator and receives the heads of the type bars. The ends 15 of the arms or devices 1, 1, serve to hold a card or sheet so that impressions may be satisfactorily made closely adjacent its upper edge. The devices 12 act to so hold the card in coöperation with the holding arms that satisfactory impressions may be made 20 closely adjacent the lower edge.

I claim:

1. A card holder comprising card holding arms adapted to be disposed respectively on 25 opposite sides of the printing point on a cylindrical platen and a scale carried by the arms and capable of adjustment thereon toward and from the line of print in a plane substantially tangent to the surface of the 30 platen.

2. The combination with the platen of a front strike typewriting machine of a card holder comprising vertically disposed arms adapted to be disposed respectively on 35 opposite sides of the printing point on the platen and a scale adjustably carried by the arms and capable of adjustment thereon toward and from the line of print in a plane substantially tangent to the surface of the 40 platen.

3. A typewriting machine card holder comprising separated card holding arms adapted to be disposed respectively on opposite sides of the printing point closely adjacent the platen surface and a scale extending 45 between and secured to said arms.

4. A typewriting machine card holder comprising separated card holding arms adapted to be disposed respectively on 50 opposite sides of the printing point closely adjacent the platen surface and a scale extending between and beyond and secured to said arms.

5. A typewriting machine card holder comprising separated card holding arms adapted to be disposed respectively on 55 opposite sides of the printing point closely adjacent the platen surface and a scale extending between and secured to said arms and having its ends deflected toward the front 60 of the machine.

6. A typewriting machine card holder comprising separated card holding arms adapted to be disposed respectively on 65 opposite sides of the printing point closely ad-

jacent the platen surface and a scale extending between and secured to said arms and having in its upper edge intermediate the arms a notch to receive the type bar heads.

7. A typewriting machine card holder 70 comprising separated card holding arms adapted to be disposed respectively on opposite sides of the printing point closely adjacent the platen surface and a scale extending between and adjustably secured to said arms.

8. A card holder comprising a holding and guiding roller adapted to be disposed to one side of the printing point adjacent the platen and of greater diameter at one end 80 than at the other.

9. A card holder comprising a holding and guiding roller adapted to be disposed to one side of the printing point of a front strike typewriting machine and of less diameter at 85 the bottom than at the top.

10. A card holder comprising a holding and guiding roller adapted to be disposed to one side of the printing point of a front strike typewriting machine and of gradually 90 increasing diameter from the bottom to the top.

11. A card holder adapted to coöperate with a cylindrical platen and the diameter of which increases from one end toward the 95 other so that the curvature of the periphery of the roller in the plane of its axis conforms substantially to the curvature of the platen.

12. The combination with a cylindrical 100 platen of a front strike typewriting machine of a card holder having holding and guiding arms adapted to be disposed in front of the platen on opposite sides, respectively, of the printing point and a spring pressed bail 105 hinged in rear of the platen, adapted to be independently swung into and out of operation and the transverse rod of which, when in operation, extends along the front face of the platen and guiding rolls carried by said rod and located, when in operation, on opposite sides, respectively, of the printing point above or beyond the line of print and adjacent the ends of said holding and guiding arms.

13. The combination with the cylindrical platen of a front strike typewriting machine 115 of a card holder having holding and guiding arms disposed in front of the platen on opposite sides, respectively, of the printing point and that is stationary with respect to the transverse travel of the platen, and card holding and guiding devices hinged in rear of and above the printing line and adapted to be swung rearwardly out of operative position and to be swung independently of the card holding arms down into operative position adjacent the ends of said arms and above them and the printing line.

14. The combination with the cylindrical 120

5 platen of a front strike typewriting machine of a card holder having holding and guiding arms disposed in front of the platen on opposite sides, respectively, of the printing point and that is stationary with respect to the transverse travel of the platen, and card holding and guiding devices moving with the platen hinged in rear of and above the printing line and adapted to be simultaneously 10 swung rearwardly out of operative position and to be simultaneously swung independently of the card holding arms down into operative position adjacent the ends of said arms and above them and the printing 15 line.

15. The combination with a cylindrical platen of a visible typewriting machine, of a card holder stationary with respect to the transverse travel of the platen, located in front of the platen and adapted to hold a card against the printing surface thereof, and a bail moving with the platen and independent of the paper feed devices and whose cross rod is parallel with the axis of the 25 platen and is a card holding means and whose side arms are hinged in rear of the platen on the platen carriage and adjacent the sides thereof and which is adapted to be swung rearwardly into inoperative position and 30 forwardly over the platen into operative position with its cross rod in rear of the card holder and adjacent the printing line.

16. The combination with a cylindrical platen of a visible writing machine, of a 35 bail, independent of the paper feed devices of the machine, whose cross rod is parallel with the platen and acts as a paper or card holding means and whose side arms are hinged on the platen carriage adjacent its 40 ends and which is adapted to be swung rearwardly into inoperative position and forwardly over the platen into operative position with its cross rod above and adjacent the printing line, guiding and feeding rolls 45 carried by said bail and spring means for pressing the rolls against the platen when they are in operative position.

17. A card holder adapted to coöperate with the rotatable transversely movable 50 platen of a typewriting machine, said holder being adapted to be mounted upon a part of the machine stationary, with respect to the transverse movement of the carriage and having two arms whose ends are disposed 55 above the line of print and respectively on opposite sides of the printing point and a cross bar bearing a scale and connecting the two arms at or below the line of print.

18. A card holder adapted to coöperate 60 with the rotatable transversely movable platen of a typewriting machine, said holder being adapted to be mounted upon a part of the machine stationary with respect to the

transverse movement of the carriage and having two arms whose ends are disposed 65 above the line of print and respectively on opposite sides of the printing point and a cross bar bearing a scale and connecting the two arms at or below the line of print combined with a bail whose side arms are pivotally mounted on the platen carriage and whose bail when in operative position bears upon the face of the platen above the ends of the card holder arms, said bail being adapted to be thrown back into inoperative 70 position when printing upon sheets is being done.

19. A card holder adapted to coöperate with the rotatable transversely movable platen of a typewriting machine, said holder 80 being adapted to be mounted upon a part of the machine stationary with respect to the transverse movement of the carriage and having two arms terminating in rollers whose axes are transverse to that of the 85 platen said rollers being disposed above the line of print and on opposite sides respectively of the printing point.

20. A card holder adapted to coöperate with the rotatable transversely movable 90 platen of a typewriting machine, said holder being adapted to be mounted upon a part of the machine stationary with respect to the transverse movement of the carriage and having two arms terminating in rollers 95 whose axes are transverse to that of the platen said rollers being disposed above the line of print and on opposite sides respectively of the printing point and a cross bar bearing a scale and connecting the two arms 100 of the card holder.

21. A card holder adapted to coöperate with the rotatable transversely movable platen of a typewriting machine, said holder being adapted to be mounted upon a part 105 of the machine stationary with respect to the transverse movement of the carriage and having two arms terminating in rollers whose axes are transverse to that of the platen said rollers being disposed above the 110 line of print and on opposite sides respectively of the printing point combined with a bail whose side arms are pivotally mounted on the platen carriage and whose bail when in operative position bears upon the face 115 of the platen above the ends of the card holder arms, said bail being adapted to be thrown back into inoperative position when printing upon sheets is being done.

In testimony whereof, I have hereunto 120 subscribed my name.

EDWARD B. HESS.
